UNITED STATES PATENT OFFICE.

JOSEPH O. TURNER, OF WINSTON-SALEM, NORTH CAROLINA, ASSIGNOR TO MENGEL COMPANY, OF LOUISVILLE, KENTUCKY.

FASTENER FOR CRATES.

Application filed August 10, 1926 Serial No. 128,453.

This invention appertains to improvements in crates, and relates more particularly to a stay or fastener adapted to be used in locking rack-strips or slats to the sides of a crate.

5 The main object of the present invention is to provide an improved form of brace or fastener which is so constructed that it will fit over the rack-strip and the side of the crate, and at the same time grip both members and thus prevent the sides of the crate from bulging. As these rack-strips or partitions form the strengthening or reinforcing means of a crate, it is extremely desirable that they be securely fastened to the sides and the 10 15 present fastener is designed to form a strong and rigid connection between these members as well as to prevent the bulging action just mentioned.

In the drawing:

20 Fig. 1 is a plan view of my improved fastener as it is struck from a piece of metal;

Fig. 2 is a perspective view of the fastening means bent to the form which it ultimately assumes when fully positioned;

25 Fig. 3 is a perspective view of an ordinary bottle crate with my fastening means applied thereto;

Fig. 4 is a vertical section of the joint as indicated by the IV—IV line of Fig. 5;

30 Fig. 5 is a horizontal section of the joint as indicated by the V—V line of Fig. 4;

Fig. 6 is another vertical section of the joint taken on the VI—VI line of Fig. 4;

35 Fig. 7 is a perspective view of a modified form of my fastener which is also bent to its ultimate shape.

The fastener designated generally by 1 is preferably stamped from a piece of sheet metal as shown in Fig. 1, and assumes in this 40 form the outline of a T. The main or body portion 2, has oppositely disposed flanges or tongues 3 and 4 extending therefrom, and has an elongated widened portion from which a tongue 5 extends. Diagonal slits or notches 45 are cut in the flanges 3 and 4 to form the spurs or prongs 6, 7, 8, 9, 10, 11, 12 and 13, while a notch is also made in the flange 5 to form the spurs 14 and 15.

In forming the fastener shown in Fig. 2 50 from the blank form, the tongues 3, 4 and 5 are bent along the dotted lines shown in Fig. 1, substantially at right angles from the body portion, while the spurs are bent inwardly from the tongues until the correspondingly opposite spurs on tongues 3 and 4,

such as 6 and 10; 7 and 11, etc., are pointing toward each other, while the spurs 14 and 15 assume a position beneath and parallel to the elongated body portion. It is to be understood, of course, that the members 3 and 4 and the tongue 5 will not be turned completely down prior to placement of the fastener in position but sufficient spread is left to allow the spurs to pass over and down along the elements into which they are to be driven. 60 65

In Fig. 3 I have shown the customary bottle crate 16, having longitudinal rack-strips 17 and transverse rack-strips 18 positioned within, which serve as partitions to separate the articles placed in the crate. The transverse rack-strips 18 fit into slots in the sides 19 and 20, and are slotted at intervals to provide for the longitudinal strips 17 which maintain the strips 18 in position. The strips 17 fit into slots in the ends 21 and 22 70 75 of the crate, and are held therein by metal reinforcing bands 23 which fit in sunken portions so that the strip will be flush with surface of the crate.

In order to additionally strengthen the 80 crate and to prevent bulging, one or all of the transverse rack-strips 18 are secured to the sides 19 and 20 by means of my fastener. The fastener may be applied to the joint, for example, by bending the flanges 3 and 4 over 85 the sides of the rack-strip and forcing the spurs into the sides of the rack-strip, then the tongue 5 is bent over the side of the crate to draw it in close contact with the rack-strip and the spurs 14 and 15 impressed into the 90 side of the crate as shown. Likewise the fastener may be applied in the opposite manner, that is by first forcing the spurs 14 and 15 into the side of the crate and then bending the flanges 3 and 4 over the rack-strip. 95

In the latter case the parts are drawn into a closer engagement due to the shape of the spurs 6 and 10, which, when forced into the rack-strip tend to move it into the joint. In addition it should be noted that the pairs of spurs 7 and 11; and 8 and 12 are so inclined as to draw the body portion downward thereby making the fastener substantially flush with the surface of the joining members. Also a machine may be utilized to attach the fastener, one part of which would force the spurs 14 and 15 into the side, and another would close the flanges 3 and 4 over the rack-strip and then close in forcing the spurs into the rack-strip. 100 105 110

Figures 4 to 6 inclusive, are merely illustrative to show in section the position the several spurs assume when forced into the wood.

Fig. 7 is a modified and somewhat simplified form of my fastener, in which the spurs on the tongues 3 and 4 are formed in a slightly different manner by cutting triangular notches with the apex of the triangle substantially coincident with the edges of the tongues. The corresponding pointed pieces of metal are bent towards each other in the same manner as before.

While I have described particularly the use of my fastener on a mortise and tenon joint, it should be understood that it may be as readily utilized where the members to be braced are merely in an abutting relation.

The structure shown provides a rigid crate, with no metallic projecting portions either on the interior or exterior, that is admirably adapted to withstand the hard and rough usage to which such an article is usually subjected.

What I claim is:—

1. As a new article of manufacture, a fastener for securing the adjacent edges of two abutting members standing at right angles to each other, said fastener being formed from a single piece of sheet metal, comprising a body portion, two flanges depending from opposite sides of said body portion adjacent an unobstructed edge thereof, a third flange spaced from the other flanges by an elongated portion of the body and depending therefrom, said flanges being notched inwardly of their edges with the pointed portions bent inwardly therefrom producing spurs adapted to be forced into the elements to be secured together, and to draw said members into closely engaging aligned relation.

2. In combination with a crate body provided with transverse rack-strips positioned at right angles to the body to form pockets, of a T-shaped fastener struck from a piece of sheet metal comprising a main portion, tongues depending from said main portion, two of the tongues bent downwardly to conform with the sides of the rack-strip, a third tongue bent over the adjoining body element, and spurs on each tongue adapted to be impressed into said sides whereby the said rack-strip is drawn into closely engaging relation with said body and is locked thereagainst.

3. As a new article of manufacture a fastener for securing the adjacent edges of two abutting members, said fastener being formed from a piece of sheet metal comprising a body portion, two flanges extending from opposite sides of said body portion, spurs on said flanges forming oppositely disposed pairs, one pair of spurs having its edges so inclined as to tend to move the abutting member inward, other pairs of spurs having their edges so inclined as to tend to move the same abutting member downward when the spurs are forced into the member, a third flange spaced from the other flanges by an elongated portion of the body and depending therefrom, and spurs on said last named flange.

4. As a new article of manufacture, a fastener for crate elements which stand in abutting relation at right angles to each other, comprising a body portion having two flanges turned downwardly from opposite sides thereof at an unobstructed edge of the body, said flanges standing in parallelism and at right angles to the body, a third flange formed at the end of and at right angles to an extension of the body, said latter flange lying in a plane at right angles to the other flanges, and prongs extending inwardly from the lower edges of the flanges, said prongs being formed with inclined edges which act, when the same are driven to place, to exert a drawing action on the crate elements and bring the top edges of said elements into horizontal alignment.

5. As a new article of manufacture, a fastener for crate elements which stand in abutting relation at right angles to each other, comprising a body having a relatively narrow section which merges into a wider portion of the body, two flanges turned downwardly from opposite sides of the narrow body portion and adjacent an unobstructed edge thereof, said flanges standing in parallelism and at right angles to the body, a third flange formed at the outer end of the wider section of the body portion and at right angles thereto, said flange likewise lying in a plane at right angles to the other flanges, and prongs extending inwardly from the lower edges of the flanges, said prongs having inclined edges for drawing the crate elements into closely aligned relation.

In testimony whereof I have signed my name to this specification.

JOSEPH O. TURNER.
